UNITED STATES PATENT OFFICE

CARL L. KNUTSON, OF MAYWOOD, ILLINOIS, ASSIGNOR TO CINCH MANUFACTURING CORPORATION, OF CHICAGO, ILLINOIS, A CORPORATION OF ILLINOIS

BINDING POST

Application filed March 19, 1931. Serial No. 523,766.

My invention aims to provide improvements in binding posts.

In the drawing which illustrates preferred embodiments of my invention:—

5 Figure 1 is a plan section of a binding post installation taken on the line 1—1 of Fig. 2;

Fig. 2 is an elevation view of a binding post attached to sheet material by means 10 of a nut and screw attachment;

Fig. 3 is a section taken on the line 3—3 of Figure 1; and

15 Fig. 4 is a section similar to that shown in Fig. 3, but showing the binding post attached by a rivet and showing the relation of the parts when a wire is not engaged with the binding post.

20 Referring to my invention as illustrated by the annexed drawing, I have shown a simple, durable and inexpensive binding post for making electrical connections between wires and being particularly adapted for use with radio, telephone and like installations. The particular binding post selected 25 for illustration includes a base member 1 formed from sheet metal and being hollow. The base member provides a shell, to the bottom end of which may be secured the head 2 of a screw 3 (Fig. 3) or a rivet 4 (Fig. 4) for attaching the binding post to a support 5 of any suitable material.

30 The base member 1 may be made in any suitable manner but I have shown it as being provided with a top wall 6, the central portion of which is pressed out to provide an aperture 7 surrounded by a sleeve portion 8, as best shown in Figs. 1 and 3. I have also provided apertures 9 cut into the side wall of the base member to receive a 35 wire 10 or wires as the use may require. The bottom edge 11 is rolled over the edge 40 of the head 2 of the attaching element.

45 A second sheet metal part 12 is assembled in axially shiftable relation with the base member 1 (Figs. 3 and 4) and is provided with a tubular portion 13 of substantial length extending through the aperture 7. The sleeve 8 provides a bearing for the tubular portion 13. Within the base 1 is 50 located an enlarged portion 14 bearing

against the inner face of the wall of the base 1 and connected by a flange 15 to the tubular portion 13, as illustrated.

A spring 16 is interposed between the closed end 17 of the tubular portion 13 and 55 the head 2 of the attaching member thereby normally pressing the flange 15 toward the top wall 6 of the base member 8.

While it is not necessary I have provided a finger piece 18 attached to the upper end 60 of the tubular portion 13 thereby to provide means to press against when it is desirable to move the axially movable part 12 against the pressure of the spring 16.

65 It is of course, apparent that the binding post is easily assembled by first inserting the tubular portion 13 through the aperture 7 from the open bottom of the base 1. The spring 16 is then introduced and finally the head 2 of the attaching member is placed 70 against the spring and the edge 11 of the base is rolled over the head 2 to hold the parts in assembled relation.

75 My improved binding post is particularly useful because a piece of wire may be easily and quickly attached by merely pushing an end through one of the apertures 9 (Fig. 1) as the axially movable member is pressed downwardly, thereby inserting the wire between the flange 15 and the top wall 6. It 80 should be noted that I have bent the top wall 6 adjacent to the apertures 9 to provide curved portions 6^a which closely engage the wire to hold it against accidental removal laterally while being yieldable to permit 85 lateral engagement or disengagement when it is desirable to engage or disengage the wire in that manner as compared to a straight line engagement or disengagement. When the pressure is released from the 90 finger piece 18 the wire is gripped tightly.

95 A wire may be entered into one of the apertures from almost any angle and, since it is not necessary to align any aperture or groove in the part 12 with an aperture 9, my device is particularly desirable.

As will be understood by those skilled in the art, another connecting wire may be attached to the screw 3 between the nut 19 (Fig. 2) and another nut (not shown) or 100

to the contact 20 (Fig. 4) by soldering, depending upon the use and the conditions. It should also be understood that "wire" means the bare end of a piece of electrical current conducting cable, a tip member, such as is used on phone cords and the like and that the "wire" may be engaged and held by the binding post when it is slipped into an aperture 9 either sidewise, endwise, or from practically any angle.

While I have illustrated and described preferred embodiments of my invention, I do not wish to be limited thereby, because the scope of my invention is best defined by the following claims.

I claim:

1. A binding post having a hollow tubular base part adapted to be attached in fixed relation to a supporting structure, said base part having an aperture in the upper end smaller in diameter than the diameter of said base part and having a wire-receiving aperture at its periphery, an axially movable member having a portion extending through the aperture in the upper end of said base part to permit operation of said member and having an enlarged portion confined within the base part and bearing against the inner surface of the tubular base part, an annular shoulder formed at the extreme upper end of the enlarged portion of said axially movable member and providing the only means of the axially movable member for engagement with a wire entered through the wire-receiving aperture in the base part and a spring normally pressing said enlarged portion toward the upper end of said base part to grip a wire between said annular shoulder and the material of said base part adjacent to the wire-receiving aperture therein.

2. A binding post having a hollow tubular base part adapted to be attached in fixed relation to a supporting structure, said base part having an aperture in the upper end smaller in diameter than the diameter of said base part and having a series of wire receiving apertures around its periphery, an axially movable sheet metal member having a hollow portion extending through the aperture in the base part to permit operation of said member and having an enlarged flange portion confined within the base part, a spring normally pressing said enlarged flange portion toward the upper end of said base part to grip a wire between said enlarged flange portion and the upper end of said base part when inserted into an aperture in said base part, an attaching part having a head secured to the lower end of said base part and said spring being interposed between the head of said attaching part and the upper end of said hollow portion of said axially movable member.

3. A binding post having a hollow tubular base part adapted to be attached in fixed

relation to a supporting structure, said base part having an aperture in the upper end smaller in diameter than the diameter of said base part and having a wire receiving aperture at its periphery, an axially movable sheet metal member having a hollow portion extending through the aperture in the base part to permit operation of said member and having an enlarged flange portion confined within the base part, a spring normally pressing said enlarged flange portion toward the upper end of said base part to grip a wire between said enlarged flange portion and the upper end of said base part when inserted into the wire receiving aperture in said base part, an attaching part having a head secured to the lower end of said base part and said spring being interposed between the head of said attaching part and the upper end of said hollow portion of said axially movable member.

4. A binding post including two hollow sheet metal parts one of which comprises a base member having an aperture in its top and a wire receiving aperture at its periphery and the other of which comprises an axially movable member having a wire clamping flange movable within the base member and a hollow portion extending through the aperture in the top of the base member for operation of said flange in combination with a spring normally pressing upon said axially movable member to clamp a wire between said flange and the top of said base when the wire is inserted into the wire receiving aperture in said base member and said top of said base having its edge bent downwardly adjacent to said wire receiving aperture for the purposes described.

5. A binding post having a sheet metal base member 1 and an axially movable member 12 assembled therewith, said base member having a top wall 6 through which is provided an aperture 7 and said base also having an elongated aperture 9 to permit the insertion of a wire directly beneath the top wall 6, said axially movable member 12 having a portion 13 extending through the aperture 7 to permit operation thereof and having an enlarged portion 14 movable in the base and connected by a flange 15 with the portion 13 and a spring 16 normally pressing said flange 15 toward said top wall 6 to grip a wire between them when said wire is inserted into the aperture 9 and said top wall 6 having a downwardly bent portion 6a to engage the wire for the purposes described.

6. A binding post having a sheet metal base member 1 and an axially movable member 12 assembled therewith, said base member having a top wall 6 through which is provided an aperture 7 of smaller diameter than the diameter of the base member and said base also having an aperture 9 close to

the top wall 6 and angled relative to a radial line transverse to the axis of the base member to permit the insertion of a wire directly beneath the top wall 6, said axially 5 movable member 12 having a portion 13 extending through the aperture 7 to permit operation thereof and having an enlarged portion 14 located entirely within the base and movable axially relative thereto, a 10 flange 15 connecting the enlarged portion 14 with the portion 13 and a spring 16 normally pressing said flange 15 toward said top wall 6 to grip a wire between them when said wire is inserted into the aperture 9.

15 7. A binding post having a sheet metal base member 1 and an axially movable member 12 assembled therewith, said base mem-

ber having a top wall 6 through which is provided an aperture 7 and said base also having an aperture 9 to permit the insertion of a wire beneath the top wall 6, said axially movable member 12 having a portion 13 extending through the aperture 7 to permit operation thereof and having an enlarged portion 14 movable in the base and connected by a flange 15 with the portion 13 and a spring 16 normally pressing said flange 15 toward said top wall 6 to grip a wire between them when said wire is inserted into the aperture 9, and said base 1 having a sleeve 8 surrounding said aperture 7 to provide a bearing for the portion 13 of the part 12. 70 75 80
